UNITED STATES PATENT OFFICE

125,149

DESIGN FOR A CIGARETTE ASH TRAY OR THE LIKE

Harold B. Donaldson and Oscar V. Romberg,
Madison, Wis.

Application September 25, 1940, Serial No. 95,362

Term of patent 3½ years

To all whom it may concern:

Be it known that we, Harold B. Donaldson and Oscar V. Romberg, citizens of the United States, residing at Madison, in the county of Dane and State of Wisconsin, have invented a new, original, and ornamental Design for a Cigarette Ash Tray or the like, of which the following is a specification, reference being had to the accompanying drawing, forming part thereof.

Figure 1 is a perspective view of a cigarette ash tray or the like showing my new design.

Figure 2 is a top plan view thereof.

Figure 3 is an end elevational view.

Figure 4 is a side elevational view.

We claim:

The ornamental design for a cigarette ash tray or the like, as shown.

HAROLD B. DONALDSON.
OSCAR V. ROMBERG.
